UNITED STATES PATENT OFFICE.

THOMAS DURRANCE, OF LEICESTER, ENGLAND, ASSIGNOR TO UNITED SHOE MACHINERY CORPORATION, OF PATERSON, NEW JERSEY, A CORPORATION OF NEW JERSEY.

WORK SUPPORT.

Application filed October 2, 1920. Serial No. 414,224.

To all whom it may concern:

Be it known that I, THOMAS DURRANCE, a subject of the King of England, and residing at Leicester, Leicestershire, England, have invented certain Improvements in Work Supports, of which the following description, in connection with the accompanying drawings, is a specification, like reference characters on the drawings indicating like parts in the several figures.

This invention relates to machines for operating upon boots and shoes and more especially to work supports, and is disclosed for illustrative purposes as embodied in an automatic edge setting machine of the type described in United States Letters Patent No. 1,078,684, granted November 18, 1913, on the application of Keall, Gouldbourn and Jerram.

Prior to the present invention it was the custom, in using machines of the type above referred to, to clamp the toe of the shoe in proper position upon the forepart support by means of a forepart clamping mechanism, and then to bring up and set the heel clamp. While this mechanism was well designed for the purpose for which it was intended, certain conditions of work, or carelessness or lack of skill on the part of the operator sometimes prevented the production of the best results. The operator might fail to aline the shoe exactly with the heel clamp, which would then contact with it only at one side of the heel, requiring a second trial to set the shoe properly. Furthermore, the double clamping operation sometimes required more time than was convenient, two of these machines being run by the same operator, who set a shoe in one while the other was setting the edge of a second shoe.

It is therefore an object of the present invention generally still further to improve shoe jacking mechanism, by providing an arrangement insuring the proper location of a shoe, for example, in machines of the type referred to, in one accurate and rapid operation.

I have therefore provided a novel organization of forepart clamping and heel clamping members constructed for dependent setting in one operation. This does away with the double clamping operation heretofore practised, and has proved to be very economical of time. Preferably the mecha-

nism is organized so that a single movement of the lever controls the positioning of both clamping members, and in the machine shown there is provision for timing so that one clamping member is set just before the other, thus permitting the operator to make a final adjustment of the shoe against one clamping member before setting the other.

The machine disclosed comprises a tool arranged to operate at a station. In operation, the operator sets the shoe on a forepart support, and settles it back into a heel clamping member which is automatically variably positioned under the pressure of the shoe as the operator adjusts the forepart of the shoe at the station. The operator then, through a single operation, sets both clamping members. An important feature of the invention consists accordingly in a tool arranged to operate at a station, a heel clamping member arranged for movement under pressure of the shoe as the operator adjusts the shoe at the station, and a setting means for the heel clamping member operated in connection with a forepart clamping member.

These and other features of the invention comprising various combinations and arrangements of parts will be understood from the following description of an embodiment thereof in connection with the automatic edge setting machine above mentioned, and shown in the drawing.

In the disclosed embodiment of the invention, the fork 10 which, in the machine described in the patents referred to, is customarily provided to engage the heel end of the shoe is, as usual, mounted for longitudinal adjustment by a clamp 11 in a sleeve 12 itself mounted to slide longitudinally in an opening 14 in the jack frame 16. A light spring 18 is provided to hold the sleeve normally in forward position with the fork projected beyond the position it will occupy when in clamping engagement with the shoe. The upper surface of the sleeve has formed upon it a ratchet 20 adapted to be engaged by a pair of pawls 22 pivoted on the jack frame and set half the length of one of the ratchet teeth apart. Light springs 24 housed in the jack frame press upon the pawls and urge them into engagement with the ratchet the teeth of which are directed so that when either of the pawls is in engagement with the teeth of the ratchet the

fork 10 is locked against rearward movement. The pawls are provided with tails 26 in juxtaposition under the end of an arm 28 of a bell-crank lever pivoted on the jack frame, said arm being broad enough to engage both tails. The other arm 30 of the bell-crank lever is acted upon by a spring-pressed plunger 32 to urge the bell-crank lever in a direction to cause it to bear upon the tails of the pawls and lift them from the ratchet. The said other arm 30 of the bell-crank lever is pivotally connected to one end of a rod 34 the other end of which extends through and is guided by an opening 36 in that end of the jack frame in which is housed the toe clamp actuating mechanism 38 customary in the machine referred to. The toe clamp mechanism employed may be that detailed in the United States Letters Patent No. 1,153,928, above referred to, and the extremity 39 of the rod 34 is in the vicinity of the lower end of the actuating lever 40.

The construction and arrangement of the parts is such that when the operator places a shoe in the jack he first places its heel end in the heel fork 10 and moves the shoe backwardly against the spring 18 with its heel end in the fork until the shoe attains the position which he considers to be the correct one. The operator then by movement of the actuating lever 40 of the toe clamp mechanism brings the toe clamping member to bear upon the top of the shoe at the back of the toe and just before the final clamping pressure is applied by the toe clamp mechanism the actuating lever bearing on the extremity 39 of the rod 34 moves it backwardly sufficiently to swing the bell-crank lever 28-30 clear of the tails of the pawls to allow one of them to drop into the ratchet and lock the heel fork against rearward movement. The rod 34 is made adjustable in length as at 42, in order to effect accurate timing of the two clamps or holding members 10 and 38. The operator, just after the fork 10 has been locked, and before the clamping member 38 has been set, will push the shoe back firmly into the fork 10, and then, with a final short movement of the lever 40 will set the clamping member 38.

The tool carrying head 44 and the guiding and operating mechanism thereof and of the jack axis 46 are described in the Letters Patent above referred to and need not be further noticed here.

Having described my invention, what I claim as new and desire to secure by Letters Patent of the United States is:—

1. In a machine of the class described, a support for a shoe, a forepart clamping member and a heel clamping member for positioning the edge of a shoe sole in the proper relation to an operating tool, and interconnecting mechanism controlling the positioning of said clamping members.

2. In a machine of the class described, a support for the tread face of a shoe, a forepart clamping member, a heel clamping member, and an operating lever constructed and arranged to move one of the clamping members to clamping position and to lock the other against movement. 70

3. In a machine of the class described, a support for a shoe, a forepart clamping member and a heel clamping member, means for locking the heel clamping member, and an operating lever, said forepart clamping member being arranged for operation by the lever in timed relation to the locking of the heel clamping member. 75

4. A machine according to claim 1 in which the interconnecting mechanism is arranged for relatively timing the final positioning of the clamping members to permit a final adjustment of the shoe against one 85 before it is finally clamped by the other.

5. In a machine of the class described, a support for the forepart of a shoe, a heel clamping member, means for automatically variably positioning said member with respect to the forepart support, and an operator controlled forepart clamping member operable to clamp the forepart against the support. 90

6. In a machine of the class described, a support for a shoe, a heel clamping member constructed and arranged to be positioned under pressure exerted by the shoe in the hand of the operator, a forepart clamping member, and operating means to lock the heel clamping member when a desired position has been reached, and to clamp the forepart against the support. 100

7. A machine according to claim 6 in which the operating means is arranged to time the locking of the heel clamping member to occur just before the forepart clamping to permit the operator to give the shoe a final pressure into the locked heel clamping member before setting the forepart 110 clamping member. 110

8. In a machine having a tool constructed and arranged for operation on a shoe and a jack arranged to support the shoe adjacent to the tool, a heel clamping member arranged to support the heel end of the shoe and movable correspondingly to the shoe length, to permit adjustment of the shoe relatively to the tool, a forepart clamping member, and means for operating the forepart clamping member and locking the heel clamping member. 115

9. A machine according to claim 8 in which the operation of the locking means and the operation of the forepart clamping member are relatively timed. 125

10. In a machine of the class described, a V-shaped member arranged to support the heel end of a shoe, and to slide resiliently to operative position under pressure from the 130

shoe, a support for the forepart upon which the shoe may be adjusted by permissive movement of the said V-shaped member to place the toe in desired position, a toe clamping member to hold the shoe rigidly to the support, and a locking means for the V-shaped member constructed and arranged to arrest the sliding movement and hold the member firmly against pressure, operated in time relation to the toe clamping member by a single effort of the operator.

11. In a machine of the class described, a support for the sole of a shoe, a forepart clamping member for securing the forepart of the shoe to the support, a heel clamping member mounted to slide under pressure from the heel end of the shoe, and mecha-

nism controlled in the movement of the forepart clamping member for locking the heel clamping member in position.

20

12. In a machine of the class described, a support for the sole of a shoe, forepart clamping means for holding the forepart of the shoe against the support, a heel clamping member for engagement with the heel end of the shoe and having a slideable stem, a spring pressed pawl for locking the stem, means normally holding said pawl out of locking position, and mechanism controlled by the forepart clamping means for releasing said holding means.

25

13. In testimony whereof I have signed my name to this specification.

THOMAS DURRANCE.
